WILLIAM W. WILSON, OF GENEVA, WISCONSIN.

Letters Patent No. 88,935, dated April 13, 1869.

IMPROVED WASHING-MACHINE.

The Schedule referred to in these Letters Patent and making part of the same.

To all whom it may concern:

Be it known that I, WILLIAM W. WILSON, of Geneva, in the county of Walworth, and State of Wisconsin, have invented a new and improved Household-Machine; and I do hereby declare that the following is a full, clear, and exact description thereof, which will enable others skilled in the art to make and use the same, reference being had to the accompanying drawings, forming part of this specification, in which—

Figure 1 is an end view of my invention.

Figure 2 is a side view of the same.

Figure 3 is a sectional elevation of the same, the section being taking through the line $x\ x$, fig. 1.

Figure 4 is a detail section at the line $y\ y$ of fig. 2. Similar letters of reference indicate like parts.

The object of this invention is to produce an improved household-machine, by combining in the same general machine a washing-machine and churn, and in so devising the mechanism of the same that either can be operated separately or together in a simple and effective manner.

My invention will be better understood by referring to the drawings, in which—

A is the box, or tub of the washing-machine. The tub is constructed with side-boards, of wood, with a curved bottom, of sheet-zinc.

This tub is divided into two equal compartments, by means of a centre-board, B, against which board the clothes are squeezed in the washing-operation, by means of the vibrating squeezing-frames C D, each of which consists of two arms, C, connected at the bottom by a flat rubbing-piece, D, having a rounded edge, as shown in fig. 3.

The arms are pivoted on a rod, a , and vibrate thereon as a centre.

E G is the general frame of the machine, and supports the tub, and affords the bearings of the main shaft H, which bears the short working-beams I, the ends of which latter are connected with the squeezing-frames, by means of rods J J', as shown, whereby the said squeezing-frames will be actuated to and from the centre-board B, as the shaft H is oscillated, and the said frames, in being so actuated, will press the clothes against the board B, and squeeze them, thereby cleansing them.

The shaft H is oscillated by means of a segmental eccentric-pulley, M, mounted on the said shaft, and connected, by means of a flexible band, K, with the segmental pieces b, affixed near each end of a vibrating hand-lever, L.

The band K is affixed to the upper part of the periphery of the oscillating pulley M, and wraps on either of the segmental pieces b, and on the periphery of the eccentric-pulley M, when the machine is in operation.

The lever L is not hung directly on a pivot, but is provided with an arm, N, projecting downward from

its middle point, the lower end of this arm being pivoted to some fixed point of the machine, as the pivot d, projecting from the side of the tub.

Each end of the lever L is provided with a handle, O, as shown, by means of which the attendant operates it.

The mechanism thus far described refers solely to the washing-machine, and the advantages are as follows:

When the pulley M is oscillated to its greatest extent in either direction, the eccentric-pulley M acts with greatest leverage, for the belt is in the position of a tangent to one of the longest radial lines of the pulley. This relation is partially produced by reason of the lever L vibrating on an arm, N, as described, but mainly by the eccentricity of the pulley M.

The arm N changes the relative position of the segmental pieces b, thereby carrying the point of attachment of band with the lever further outward from the vertical centre line of the lever, and thus bringing the band K in a tangent line with one of the greatest radii of the pulley, as aforesaid.

The cosine of the angle made by the working-beams is also shortened, thus increasing their leverage on the squeezing-frames.

These relative conditions of the pulley, band, lever, and working-beams, operate to obtain great pressure of the squeezing-frames upon the clothes when the latter are compressed to the fullest extent, and this terminal pressure, which is most effective in cleansing, is obtained with the same, or only a slight increase in the power required to actuate the machine in its intermediate movements.

The two parts J and J' of each connecting-rod are pivoted together, thus affording a jointed rod, which permits the parts J' to be folded up, in order to raise the squeezing-frames sufficiently high for the insertion of clothes.

A second stud, or pin, is required to hold the two parts J and J' rigid, so as to operate as a single rod, and this pin is affixed to and held in place by a spring, e, the lower end of which is affixed to the part J'.

The pin, thus held, passes through both of the parts J J', and contributes to produce a rigid joint.

When the parts J' are to be folded up, the springs are drawn back, which withdraws the pin from one of the parts, and thus permits the said parts J' to work on the pivot, connecting it with the part J.

The part D of the squeezing-frame acts to roll the mass of clothes over at each impingement, thus presenting them in a new position for the next impingement, which operation conduces to their more perfect and speedy cleansing.

The return-body, P, is affixed to the washing-machine in any suitable manner, so that it shall be nearly under the straight part, or arms f f, of the pulley M.

The dasher-staff is formed of two semi-cylindrical halves, *g g*, which are arranged with their plane surfaces in contact, thus forming a cylindrical staff.

Each part bears one-half of the dasher or dashers, which are operated in contrary directions, thus causing a rolling or abrupt fluctuation of the cream, which conduces to the speedy production of butter.

Each part of the dasher-staff is connected with the part *f* of the pulley, by rods *h h*, as shown, the lower ends of which are held in the slotted ends of each staff *g* by removable pins *i*.

The churn, thus connected, derives its motion from the washing-machine, but I have provided other mechanism, by means of which the churn may be operated separately.

It will be observed that by pulling out the pins *i i*, the rods *h* will be disconnected from the churn-staves *g*, and the washing-machine left free to be worked separately, if desired; and, should it be desired to work the churn separately, the mechanism hereinafter described will be used.

Q Q are two uprights, resting in sockets *c*, affixed to the churn, near the base of the same.

One of these uprights is slotted, to receive a lug, *k*, affixed to the churn, near its top. The slot and lug constitute a simple device for preventing the uprights from slipping out of the sockets when the mechanism is in operation, but which enables the said uprights and their accessory mechanism to be easily removed when required.

The upper ends of the uprights are connected by a pair of arched plates, *l l*, which afford bearings for the pin *m*, on which the segmental pulley *R* oscillates.

n n are the rods, similar to the rods *h*, and connect the pulley *R* with the two parts of the churn-staff, each rod being pivoted in the slotted end of its respective part, or staff *g*.

The oscillating pulley *R* is connected by a band, *o*, with the segmental shoes *p p* of a hand-lever, *S*, having handles *q*, and pivoted to a block, *w*, (see fig. 4,) affixed as a cross-brace between the uprights *Q Q* of the churn-mechanism.

As the hand-lever is vibrated, the pulley *R* is oscillated, and, being connected by the rods *n n* with the dasher-staves *g g*, the latter are operated in opposite directions.

i i are the removable pins, which pass through the slotted ends of the staves *g g*, and through the rods *n n* or *h h*, thus connecting either pair of rods with the staves.

One of the pins connecting the plates *l l* with the uprights *Q Q* is formed with a handle, *j*, so that it may

be easily drawn out to separate the independent churn-mechanism from the churn, when the latter is to be driven by the washing-machine.

The pin *j* being thus drawn out, the plates *l* are turned back, the band *o* on that side being first slipped off from its segmental piece to permit the said plates turning back on the other pin as a hinge.

The button-plate *u*, (see fig. 4) which closes the recess in the block *w*, through which the churn-staves work, is then turned away from the fixed plate *v*, which it meets with a bevelled joint to hold it when in place. The upright *Q* is then moved away from the lug *k* on the churn, and both uprights are lifted from the sockets and removed. The rods *h h* are then connected with the staves *g g*, as before.

T is a guide-block for the staves.

Its recess is closed by a button-plate, *r*, and fixed plate *t*, similar to *u v* in fig. 4. This block is affixed to the washing-machine in any suitable manner.

The bands *K* and *o* are attached to the inner side of their respective segmental pieces, and pass down and under the lower ends, and up in contact with the faces of the same, as shown, so that by slipping off the bands they will remain slack and inoperative.

Having thus described my invention,

I claim as new, and desire to secure by Letters Patent—

1. The combination, in a washing-machine, of the semicircular tub *A*, shafts *H*, eccentric-pulley *M*, working-beams *I*, rods *J*, squeezing-frames *C D*, each working in a separate compartment, substantially as and for the purpose herein shown and described.

2. The combination, with the above-claimed parts, of the jointed rods *J J'* and pin-spring *e*, substantially as and for the purpose herein shown and described.

3. The hand-lever *O L N*, segment pieces *b*, and belt, or band *K*, in combination with the pulley *M*, for imparting a vibrating motion to the squeezing-frames *C D*, as herein shown and described.

4. The combination, in a machine for household use, of the churn *P*, having double dasher-staves *g g*, connected by means of rods *h h*, with the eccentric-pulley *M* of the washing-mechanism, substantially as and for the purpose herein shown and described.

5. The churn-mechanism *Q Q*, *R*, *l l*, *o*, *S*, *q*, *p*, *n n*, substantially as described, in combination with the double churn-staves *g g* and churn *P*, substantially as and for the purpose herein shown and described.

WILLIAM W. WILSON.
